DESIGN FOR A CHRISTMAS TREE ORNAMENT

Sol D. Cohen, New York, N. Y., assignor to Paper Novelty Manufacturing Co., New York, N. Y., a corporation of New York

Application January 27, 1938, Serial No. 74,591

Term of patent 7 years

To all whom it may concern:

Be it known that I, Sol D. Cohen, a citizen of the United States and resident of the city, county, and State of New York, have invented a new, original, and ornamental Design for a Christmas Tree Ornament, of which the following is a specification, reference being had to the accompanying drawing, forming a part thereof, and in which

The dominant feature of my design resides in the base layer which is cupped in dish form.

I claim:

The ornamental design for a Christmas tree ornament as shown and described.

SOL D. COHEN.
